PROCESS FOR PRODUCING INDENES

William E. Elwell, Berkeley, Calif., assignor to
California Research Corporation, San Francisco, Calif., a corporation of Delaware

Application July 1, 1948, Serial No. 36,356

12 Claims. (Cl. 260—668)

1

This invention relates to a process of producing indene compounds and refers particularly to a process for dehydrogenation of ethyl toluene and ethyl xylene for the production of indene and methyl indene.

This invention involves the discovery that when ethyl toluenes and ethyl xylenes are dehydrogenated there is produced not only the corresponding vinyl toluene and vinyl xylene compounds, but there may also be produced indenes. In order to produce indenes by dehydrogenation, it is necessary that the ethyl toluene or xylene subjected to the dehydrogenation treatment contain a methyl group adjacent to the ethyl group, that is to say, indene may be produced by the dehydrogenation of ortho ethyl toluene or by the dehydrogenation of the 2,3-dimethyl 1-ethyl benzene, the 2,4-dimethyl 1-ethyl benzene, the 2,5-dimethyl 1-ethyl benzene, or the 2,6-dimethyl 1-ethyl benzene, dehydrogenation of the ethyl xylenes yielding corresponding methyl indenes.

The formation of indene compounds by dehydrogenation appears to be a two-step process. In the first step of the process the ethyl compounds are dehydrogenated to form the vinyl compounds. Thus, for example, on dehydrogenation of the 2,5-dimethyl 1-ethyl benzene there is produced the 2,5-dimethyl 1-vinyl benzene. Then by a subsequent dehydrogenation operation the 2,5-dimethyl 1-vinyl benzene becomes dehydrogenated to a methyl indene as indicated by the following reaction.

The particular methyl indenes made by this process (i. e. where the methyl group is attached to the benzene nucleus) do not appear to have been previously described, and these methyl indenes, therefore, as well as their process of production, appear to be novel products. The process of producing indenes, including methyl indenes, of the present invention, will be more fully understood from the following description of a preferred example of a process embodying the invention, which description is given in connection with the accompanying drawings.

In the drawings the figure represents a diagrammatic view of a suitable apparatus in which the process of the present invention may be conducted, in which drawing, however, for the sake

2

of clarity and simplicity, there have been omitted certain details such as pumps, valves, measuring means, heat-exchangers, coolers, refluxing apparatus, flow meters, and like appurtenances, as will be readily supplied by one skilled in the art.

In the process, as illustrated in the drawing, an ethyl toluene or ethyl compound enters through line 1 into the dehydrogenator 2. When the normal indene is desired, the feed material should be ortho ethyl toluene, whereas, if one of the novel methyl indenes of the present invention is desired as the product, then the feed material is selected from the group of ethyl xylenes including the 2,3-dimethyl 1-ethyl benzene, the 2,4-dimethyl 1-ethyl benzene, the 2,5-dimethyl 1-ethyl benzene, and the 2,6-dimethyl 1-ethyl benzene.

Within the dehydrogenator 2 the ethyl toluene or xylene is brought into contact with the dehydrogenation catalyst. Such dehydrogenation catalyst may, for example, be the Houdry type catalyst, which consists generally of about 10% chromium oxide Cr_2O_3 on an alumina Al_2O_3 support, or may consist of a chromium phosphate catalyst on an inert support, or may comprise the so-called iron catalyst, which are mixtures containing iron oxide Fe_2O_3 , potash K_2O , and magnesium oxide MgO .

When the chromium oxide catalyst is employed, a temperature of dehydrogenation of around 1100° F. to 1150° F. is generally employed in the dehydrogenator 2. In the case of other catalysts, somewhat higher reaction temperatures of about 1200°-1300° F. are maintained in the dehydrogenator 2.

With the chromium oxide catalyst a vacuum is normally employed in the dehydrogenator corresponding to about 5 in. Hg absolute, whereas atmospheric pressure is commonly employed with the other catalysts mentioned. In operation of the process, using the chromium oxide catalyst, the usual practice may be followed of interrupting the dehydrogenation operation periodically, such, for example, as about every fifteen minutes, whenever the percentage of coke deposited in the dehydrogenator rises to about 1 to 5 percent. On interruption of the operation, air, at substantially the reaction temperature, is introduced into the dehydrogenator to burn out the produced coke, which operates at the same time to elevate the temperature of the dehydrogenator about 50° C. With the iron oxide catalyst, steam is continually supplied to the hydrogenerator. A proper proportion of steam to feed material is around 2-3 to 1.

Under these operating conditions, a conversion of about 15 to 35% of the ethyl toluene or ethyl xylene to either vinyl compounds or indenes occurs in each pass through the dehydrogenation apparatus. The higher temperatures of operation yield the higher ratio of indenes to vinyl xylene production.

From the dehydrogenator 2 the unreacted material and the produced products are passed through a heat exchanger 4 into a still 5. In the cooler 4 the product of the dehydrogenator 2 is rapidly cooled to a low temperature such as 50° C. in order to inhibit polymerization of the vinyl material present. In the still 5 the entering material is subjected to distillation under vacuum assisted by steam, and thus distillation is carried out while the material in the still is maintained saturated with an inhibitor of polymerization, such as sulphur. A temperature of distillation in the still of around 75° to 90° C. is maintained while steam is introduced as by a line 6 in the ratio of 2 to 5 parts by weight of steam to 1 part of hydrocarbon material undergoing distillation, in order to vaporize and remove the unreacted ethyl toluene or ethyl xylene. The still 5 will require about 60 to 90 plates in the separating column where ethyl xylene is feed material, in order to effect the desired separation of the unreacted ethyl xylene from the produced vinyl compound and indenes. The distillation column should be maintained under vacuum corresponding to about 20 to 50 mm. Hg at the top of the column in order to be able to effect the desired vaporization at a temperature of 75° to 90° C.

In order to prevent polymerization of the vinyl compound in this operation, the distillation system should be maintained saturated with sulphur, for which purpose I have indicated a saturator 7 which should contain sulphur. In the process a part of the ethyl xylene should be recirculated by line 8 through the sulphur saturator 7 and back into the column of the distillation still 5 in order to maintain the contents therein saturated with sulphur. The unreacted ethyl xylene which is separated from the top of the still 5 is recycled by lines 9 and 10 to dehydrogenator 2.

From the still 5 the vinyl compounds and indenes, and any tar products in the process, are passed through line 11 into a second distillation separation still 12 wherein it is again subjected to distillation under vacuum and by the aid of steam in order to vaporize and remove from the system the vinyl xylene product which is removed through line 13 and recycled through line 10 to the dehydrogenator 2. The same conditions of operation, except for the control of the refluxing, are maintained in still 12 as are maintained in the still 5, that is, about 75° to 90° temperature and a pressure at the top of about 20 to 50 mm. Hg absolute. The separation of vinyl xylenes from the produced methyl indene is extremely difficult, if not impossible, to effect in the distillation unit 12, so that it generally is necessary where a pure indene product is desired to allow a return with the vinyl xylene recycled through lines 13 and 10 of some of the methyl indene produced. From the bottom of the distillation unit 12, however, a product containing the methyl indenes or other indenes is withdrawn, which may contain some tar produced in the process, but which product is substantially free of the vinyl compounds. This indene product containing tar is passed through line 14 into a further distillation still and column 15, from which the desired indene material is withdrawn

as an overhead through line 16, and any tar produced is drawn through line 17.

In certain cases it is desirable to produce a product consisting of a mixture of vinyl and indene compounds. In such a case, rather than recycling the mixture of vinyl and indene compounds to the dehydrogenator through line 13, such mixture may be withdrawn as a useful product. Also, in certain cases the vinyl column 15 may be omitted and the entire vinyl and indene compounds produced in the process withdrawn as an overhead from column 12 and passed from line 13 to storage.

In the process the recycled vinyl material undergoes further dehydrogenation in a dehydrogenator 2 into the indene product. Under certain circumstances, of course, one may operate the process so as to produce two products, i. e. a vinyl toluene or xylene and an indene or methyl indene, in which case the vinyl material would not be recycled to the dehydrogenator.

As illustrative of the operation of the process of the present invention: In one example of the process 2,5-dimethyl 1-ethyl benzene was the feed product and the chromium oxide type of catalyst was utilized. The space rate in the dehydrogenation zone was maintained at about three volumes of ethyl xylene per volume of catalyst per hour, and the chromium oxide type of catalyst was employed. A temperature of operation was maintained constant during each of three runs. The temperatures of operation in the successful runs were 1040° F., 1068° F., and 1120° F. respectively. The product withdrawn from line 3 analyzed in the three respective cases 20.1%, 20.9%, and 24.8% vinyl xylenes, and 2.2%, 2.9%, and 5.2% methyl indenes. This illustrates that the higher operating temperatures are favorable to the maximum conversion to methyl indenes.

In another test operation of the process, using the same catalyst, space rate, pressure of operation, the feed material consisted of 65% of the 2,4-dimethyl 1-ethyl benzene, 25% of the 2,6-dimethyl 1-ethyl benzene, and 10% of the 3,5-dimethyl 1-ethyl benzene. Test operations at the respective temperatures of 1031° F., 1067° F., and 1118° F. were maintained. The product from the dehydrogenator in this case analyzed respectively 18.5%, 18.6%, and 21.2% vinyl xylenes and respectively 3.2%, 4.8%, and 6.9% methyl indenes.

While the particular example of the process herein described is well adapted to carry out the objects of the invention, various modifications may be made, and this invention is of the scope set forth in the appended claims.

I claim:

1. A process of producing indenes and methyl homologs thereof, by catalytic dehydrogenation which process comprises subjecting a member of the group consisting of ortho ethyl toluene, 2,3-dimethyl 1-ethyl benzene, 2,4-dimethyl 1-ethyl benzene, 2,5-dimethyl 1-ethyl benzene, and 2,6-dimethyl 1-ethyl benzene to catalytic dehydrogenation so as to produce a corresponding substituted vinyl product and indene compound and separating the indene compound from the reaction products.

2. A process of producing indene and a methyl homolog thereof, by catalytic dehydrogenation which process comprises subjecting a member of the group consisting of ethyl toluenes and ethyl xylenes containing a methyl group adjacent to the ethyl group to catalytic dehydrogenation so as to convert the ethyl compound to the corresponding substituted vinyl compound, and then

by further catalytic dehydrogenation convert a part at least thereof by cross-dehydrogenation with said adjacent methyl group to the desired indene material and separating the desired indene material from the reaction products.

3. A process of forming an indene, by catalytic dehydrogenation which process comprises subjecting a member of the group consisting of ethyl toluenes and ethyl xylenes, which contain a methyl group ortho to the ethyl group, to catalytic dehydrogenation so as to first convert a part of the ethyl material to the corresponding substituted vinyl material and to convert a portion of the vinyl material by cross-dehydrogenation with said adjacent methyl group to the desired indene material, removing the reaction product from the catalytic dehydrogenation step and separating the indene products from the unreacted ethyl material, recycling said material to the catalytic dehydrogenation step.

4. A process of producing indenes, by catalytic dehydrogenation which process comprises passing through a catalytic dehydrogenation step a member of the group consisting of the ortho toluenes and xylenes which contains a methyl group ortho to the ethyl group, therein dehydrogenating a part of the ethyl material to the corresponding substituted vinyl material and a part by cross-dehydrogenation with said ortho methyl group to the desired indene material, removing the reaction product from the dehydrogenation step and separating unreacted ethyl material and vinyl material from the produced indene and recycling the ethyl material and vinyl material to the dehydrogenation zone.

5. A process of forming an indene, by catalytic dehydrogenation which process comprises subjecting a member of the group consisting of ethyl toluenes and ethyl xylenes which contain a methyl group ortho to the ethyl group to catalytic dehydrogenation so as to first convert a part of the ethyl material to the corresponding substituted vinyl material and to convert a portion of the vinyl material by cross-dehydrogenation with said adjacent methyl group to the desired indene material, removing the reaction product from the dehydrogenation step and separating the indene products from the unreacted ethyl material and recycling said material to the dehydrogenation step, the separation being conducted in a vapor separation step in which the unreacted ethyl material is vaporized under pressure below atmospheric assisted by the introduction of steam while introducing sulphur into said vapor separation zone to inhibit polymerization of the vinyl material.

6. A process of forming an indene, by catalytic dehydrogenation which process comprises subjecting a member of the group consisting of ethyl toluenes and ethyl xylenes which contain a methyl group ortho to the ethyl group to catalytic dehydrogenation so as to first convert a part of the ethyl material to the corresponding substituted vinyl material and to convert a portion of the vinyl material by cross-dehydrogenation with said adjacent methyl group to the desired indene material, removing the reaction product from the dehydrogenation step and separating the indene products from the unreacted ethyl material and recycling said material to the dehydrogenation step, the separation being conducted in a vapor separation step in which the unreacted ethyl material is vaporized under pressure below atmospheric assisted by the introduction of steam while introducing sulphur into said vapor separation

zone to inhibit polymerization of the vinyl material, and separating the vinyl material and recycling the same to the dehydrogenation zone.

7. A process of producing indenes, by catalytic dehydrogenation which process comprises passing through a catalytic dehydrogenation zone a member of the group consisting of ethyl toluenes and ethyl xylenes having methyl groups ortho to the ethyl group, therein dehydrogenating between 15% and 35% of the entering ethyl material so as to form corresponding substituted vinyl products and by cross-dehydrogenation with said ortho methyl group the desired indene material, removing the reaction mixture from the dehydrogenation step and separating the unreacted ethyl material and recycling said material to the dehydrogenation step.

8. A process of producing indenes by catalytic dehydrogenation which comprises passing into a catalytic dehydrogenation zone a member of the group consisting of ethyl toluenes and ethyl xylenes having a methyl group ortho to the ethyl group, therein dehydrogenating between 15% and 35% of the ethyl material to the corresponding substituted vinyl compounds and desired indene material, the indene material being formed by cross-dehydrogenation between the vinyl group and the ortho methyl group, removing the reaction product from the dehydrogenation zone and separating the unreacted ethyl toluenes and ethyl xylenes and vinyl toluenes and vinyl xylenes from the produced indene and recycling such ethyl toluenes and ethyl xylenes and vinyl toluenes and vinyl xylenes to the dehydrogenation zone.

9. A process of producing indenes by catalytic dehydrogenation which comprises passing into a catalytic dehydrogenation zone a member of the group consisting of ethyl toluenes and ethyl xylenes having a methyl group ortho to the ethyl group, therein catalytically dehydrogenating a part of the ethyl material by contact with the catalyst to produce in part the corresponding substituted vinyl material and in part by cross-dehydrogenation of the ortho methyl group the indene material and separating the indene material from the reaction products by distillation.

10. A process of producing indenes by catalytic dehydrogenation which comprises passing into a catalytic dehydrogenation zone a member of the group consisting of ethyl toluenes and ethyl xylenes having a methyl group ortho to the ethyl group, therein catalytically dehydrogenating a part of the ethyl material by contact with the catalyst to produce in part the corresponding substituted vinyl material and in part by cross-dehydrogenation of the ortho methyl group the indene material and separating the indene material from the reaction products, the catalyst employed being a chromium oxide catalyst.

11. A process of producing indenes by catalytic dehydrogenation which comprises passing into a catalytic dehydrogenation zone a member of the group consisting of ethyl toluenes and ethyl xylenes having a methyl group ortho to the ethyl group, therein catalytically dehydrogenating at a temperature of about 1200°-1300° F. a part of the ethyl material by contact with the catalyst to produce in part the corresponding substituted vinyl material and in part by cross-dehydrogenation of the ortho methyl group the indene material and separating the indene material from the reaction products by distillation, the catalyst employed being an admixture of iron oxide, magnesium oxide, and potash, and intro-

7
duc^{ing} steam into the dehydrogenation zone for activating the catalyst.

12. A process of producing indenes by catalytic dehydrogenation which comprises passing into a catalytic dehydrogenation zone a member of the group consisting of ethyl toluenes and ethyl xylenes having a methyl group ortho to the ethyl group, therein catalytically dehydrogenating at a temperature of about 1000°-1300° F. a part of the ethyl material by contact with the catalyst to produce in part the corresponding substituted vinyl material and in part by cross-dehydrogenation of the ortho methyl group the indene material, about 15% to 35% of the ethyl material being dehydrogenated in one passage through the de- 15

hydrogenation zone and separating the indene material from the reaction products by distillation.
